UNITED STATES PATENT OFFICE

FRANK R. CHESTER, OF NEW YORK, N. Y., ASSIGNOR TO CHESTERFIELD CONTROL COMPANY, OF NEW YORK, N. Y., A CORPORATION OF DELAWARE

TABLE

Application filed June 11, 1930. Serial No. 460,315.

This invention relates to an article of furniture, and specifically, a support such as a table, and aims to provide a functionally and structurally improved article of this nature which, when extended, will provide an extremely rigid support and which, when collapsed, will occupy a minimum amount of space.

It is an object of the invention to furnish a support, and particularly a table, which will embody relatively few parts, each individually simple and rugged in construction, these parts being capable of ready manipulation, by a relatively inexperienced person, to permit of the provision of a small or extended table, as may be desired, and in which, moreover, this article will embody, in so far as feasible, an extremely artistic and pleasing appearance in its several conditions.

A further object of the invention is that of furnishing an article of this nature which may be set up or reduced to occupy a minimum amount of space with the least possible effort, and in which, in any of its conditions, a perfect deck surface will be presented so that while the table may be employed to advantage in any number of different associations, it will always present a surface capable of use, for example, in connection with table tennis and ping pong. Moreover, the structure will be so rigid as to be capable of withstanding the severe strains imposed on its deck and associated parts without there being any danger of the several table units becoming relatively displaced.

With these, and further, objects in mind, reference is had to the attached sheets of drawings illustrating one practical embodiment of the invention, and in which:

Fig. 1 is a perspective view of the table partially "set up";

Fig. 2 is a plan view of the main portion of the table;

Figs. 3 and 4 are enlarged sectional views taken along the lines 3—3 and 4—4 in the direction of the arrows indicated in Fig. 2;

Fig. 5 is an enlarged sectional view showing the disposition of one of the supporting legs when in extended condition;

Fig. 6 shows this part in housed condition, and

Fig. 7 is a sectional side view of one of the deck panels.

In these views, the numeral 10 indicates a base formation supporting legs 11 extending upwardly. Suitably mounted upon the upper ends of these legs is a deck section 12. At this time it will, of course, be understood that while in most respects, from an artistic viewpoint, it is desirable to have the supports 11 extend centrally of the deck section, this need not necessarily be the case. As shown in Fig. 3, the panel section 12 preferably has spaced below its under face a plate or panel 13, and disposed within the space thus provided are arms 14 pivotally supported as, for example, by bolts 15. These arms may each be formed of metal and are conveniently U-shaped in cross-section, it being noted that adjacent their inner ends a plate, or cooperating strip portion, 16 is conveniently furnished for the purpose of reinforcing them adjacent the point of contact of the bolt. Also, bearing plates 17 may be disposed in association with the inner faces of the panels with a view to providing a rigid, unitary structure which will be free, to a maximum extent, from any tendency of the parts to bind.

In the embodiment illustrated, the arms 14 support, adjacent their outer ends, legs 18. These may be of any desired construction, but preferably, are of such area that they may be accommodated within the panels existing along the under faces of the arms. A convenient form of attaching these legs to the arms is, according to the present invention, by means of transversely extending bolts 19, it being noted that the upper ends of the legs are carried, if desired, in blocks 20, the upper faces of which are beveled, as has been indicated at 21, and that the pivot points 19 are so located with reference to the side portions of the arms 14 that the inner face 21 will clear the inner face of the base portions of these arms.

The purpose of this construction is to be found in that a wedge structure is presented by preferably utilizing a spring strip 22 bent

upon itself to furnish a resilient portion lying in line with the inner face 21 of the block, when the leg is in vertical position. Accordingly, with the parts in this position, 5 it will be appreciated that the strip will act to prevent their displacement. The wedge unit thus furnished is rendered retractable by means of an actuating portion 23 extending conveniently beyond the arm with which 10 the strip is associated, and this strip is normally projected by means of a spring 24, it being noted that a stop pin 25 is utilized, if desired, to prevent any possibility of the strip, under the influence of the spring, being 15 projected to too great an extent. Moreover, the wedge structure furnished by the strip is adjustable to meet variations in manufacture and also to compensate for wear, as, for example, by employing a bolt or set screw 20 26 which passes through the outer leg of the strip and bears against the inner face of its body.

As a result of this construction, it will be readily appreciated that, with the parts 25 in the position shown in Fig. 6, the contact between the side face of the block and the outer arm of the strip will be such that the leg 18 will remain in housed condition within the body of the arm. However, by simply 30 retracting the wedge unit by means of the actuating portion 23, the leg will automatically, under the influence of gravity, swing downwardly until it occupies the position shown in Fig. 5. Of course, the operator 35 might manually swing the leg, if he so desires, but in any event, upon now releasing the actuating portion 23, the wedge structure furnished will yieldingly bear against the upper end of the leg to prevent any movement 40 of the same around its pivot 19. The purpose of preferably having the upper edges of the block extend at an angle will now be obvious, in that the under surface of the wedge unit preferably extends at such an 45 angle, and thus a proper co-operation of the parts will be assured.

It will, moreover, be observed that the upper faces of the arms 14 may each be provided with openings 26. Panels 27 may 50 be disposed in line with the panel 12 and upon the arms 14, and further panels, up to any desired number—and according to the length of the arms—may, in turn, be arranged beyond the panels 27. Of course, if merely 55 a small table is desired, the latter panels might provide the end portions of the table, with consequent reduction in the length of the arms 14. However, conceding that a table exactly of the type shown is to be assembled, panels 28 are disposed beyond the 60 panels 27 and, as shown in Fig. 7, these panels are each preferably formed with a bore within which a screw-threaded shaft 29 is disposed. A traveler 30 is bound within a 65 recess of the panel 28 and upon the shaft, and

is formed with a hook-shaped extension 31 of sufficient depth to pass through the opening 26 of the arm. It will be observed that the end of the shaft is square, as has been indicated at 32, so as to mount a suitable key 70 or crank, and accordingly, with the parts disposed in this manner, the shaft may be turned in order to draw the traveler along its body and correspondingly shift the panel 28 toward the panel 27. This latter panel will thus be pressed against the panel 12, and under suitable pressure, all of these panels may be brought to a condition where their upper faces form one continuous surface, 75 with their edge portions practically invisibly 80 merged in the deck.

In so far as structural details are concerned, it will, of course, be understood that much latitude may be had. It is preferred, according to the present invention, to have the 85 panels embodying a tongue and groove construction, as has been indicated at 33. Moreover, with reference to the blocks 20, these may conveniently include a jacketing portion 90 enclosing the upper ends of the legs 18, and within which a block 34 is disposed, this block firmly engaging the threads of a member 35 which has its upper end rotatively encircling the bolt 19, furnishing the pivot for the leg. The set-screw 26 may be provided with a 95 locking nut 36, and a brace 37 may be provided below the panel, or plate, 13 for the purpose of reinforcing the center part of the table. Finally, according to this invention, 100 strips or apron portions 38 may close the space between the panels 12 and 13, and they may be extended below the latter to conceal the housed structure, while strips 39 are pivotally mounted between the aprons 38 thus to provide a completely housed structure which, 105 however, is instantly available upon the strips 39 being swung downwardly, as shown in Fig. 3, movement beyond a predetermined point in this connection being prevented by 110 stops 40.

Reviewing briefly the operation of the structure, it will be understood that, with the parts completely housed, an extremely attractive article is presented which may be utilized for any desired purpose and will appear, for example, as a relatively small, or wall type, table. The operator, by simply swinging the strips 39 down, exposes the two pairs of arms 14, and the latter may be swung 115 outwardly around their pivotal bolts 15 to 120 extend in the manner shown in Fig. 1. Thereupon, by simply manipulating the actuating portions 23, the legs 18 may be brought to proper supporting condition, and now the panels 27 and 28 may be placed in position, 125 whereupon, by tightening these panels, a complete unitary structure will be furnished which will withstand the heaviest usage without in any way disturbing the relationship of its parts. By simply reversing the foregoing 130

- procedure, the parts may again be neatly and compactly housed and, to all intents and purposes, an ordinary piece of furniture will be presented.
- 5 From the foregoing it will be appreciated that, among others, the several objects of the invention as specifically afore referred to are achieved. It will, moreover, be understood that numerous changes in construction, and 10 rearrangements of the parts, might be resorted to without departing from the spirit of the invention as defined by the claims.
- Having described my invention, what I claim as new and desire to secure by Letters 15 Patent is:
1. A table including a panel, means for supporting the same, an arm pivotally associated with said panel, said arm being substantially U-shaped in cross-section and with its 20 legs extending downwardly, and a table leg pivotally supported between the legs of said arm.
  2. A table including a panel, means for supporting the same, arms movable outwardly from said table, legs pivotally carried by said arms and adapted to be swung in substantially vertical planes, and means for locking such legs against movements with respect to said arms, said means comprising a wedge 25 structure sliding contact with said legs adjacent their upper ends.
  3. A table including a panel, a plate spaced from the same, supporting means for said panel and plate, arms disposed between said 30 panels and plates, means cooperating with the inner ends of said arms pivotally to support the same, whereby the latter may be swung outwardly in a substantially horizontal plane and beyond said panel, and means for normally 35 closing the space between the edges of said plate and panel to provide a housing structure for said arms.
  4. A table including a panel, a plate spaced from the same, supporting means for said 40 panel and plate, arms disposed between said panels and plates, means cooperating with the inner ends of said arms pivotally to support the same, whereby the latter may be swung outwardly in a substantially horizontal plane and beyond said panel, strips pivotally supported by said table, and said strips being disposed beyond the outer edges of said plate, whereby they may close the space between 45 said plate and panel.
  5. A table including a supporting structure, arms extendible therefrom and U-shaped in cross-section, legs normally housed within said arms and extending between the sides thereof, and means for pivotally supporting the upper ends of the legs in such 50 position.
  6. A table including a supporting structure, arms extendible therefrom and U-shaped in cross-section, legs normally housed 55 within said arms and extending between the
- sides thereof, and quick, releasable means for normally locking the legs in such position.
7. A table including a supporting structure, arms extendible therefrom and U-shaped in cross-section, legs normally housed within said arms and extending between the sides thereof, and spring-projected wedging means for normally bearing against said legs to prevent movement thereof with respect to said arms. 70
8. A table including a supporting structure, arms extendible therefrom and U-shaped in cross-section, legs normally housed within said arms and extending between the sides thereof, said legs being swingable to extend at substantially right angles to the arms with which they are associated, and means for locking said legs into such latter position. 75
9. A table including a supporting structure, arms extendible therefrom and U-shaped in cross-section, legs normally housed within said arms and extending between the sides thereof, said legs being swingable to extend at substantially right angles to the arms with which they are associated, and a single means for each of said legs and co-operating therewith to lock the same against movement in both housed and extended conditions. 80
10. A table including a supporting structure, arms extendible therefrom and U-shaped in cross-section, legs normally housed within said arms and extending between the sides thereof, said legs being swingable to extend at substantially right angles to the arms with which they are associated, and spring strips disposed between the base portions of said arms and the inner ends of said legs and wedging against the latter normally to prevent movement thereof with respect to said arms. 85
11. A table including a panel, supporting means therefor, an arm extendible beyond said panel and formed with an opening, a second panel to be disposed upon said arm, and means cooperating with said arm opening and said second panel for forcing the latter along said arm and into intimate contact with said first named panel. 90
- In testimony whereof I affix my signature. 95
